FRANK W. FULLER, OF ST. PAUL, MINNESOTA

RADIATOR HANGER

Application filed October 6, 1930. Serial No. 486,528.

The present invention relates to a radiator hanger.

In the installing of radiators in buildings, it is customary to hang the radiators from the walls so as to avoid the necessity of using legs to support the radiators. This method of hanging radiators from the walls permits the radiators to be hung at any desired height from the floor and also facilitates cleaning beneath the radiators, as the old style legs interfered with the passing of a broom or mop beneath the radiators. A great many different types of mechanisms have been designed to support radiators on a wall. The present type is adapted to grip a column of the radiator by means of jaws carried by a pivotally mounted lever.

An object of the present invention is to make an improved and simplified radiator hanger.

In order to attain this object, there is provided, in accordance with one feature of the invention, a backing plate with a hollow pivotal support member mounted thereon adapted to receive a supporting bolt through the center thereof and with a lever pivotally mounted thereon adapted to receive a supporting bolt through the center thereof and with a lever pivotally mounted on said pivotal supporting member and having a pair of oppositely disposed, offset jaws adapted to grip a column of the radiator and to be held in gripping relation with said radiator by means of the weight of the radiator acting upon said offset jaws.

These and other features of the invention will be more fully brought out in the following description and the accompanying drawing, wherein:

Figure 1 is an elevation of the device, a radiator column being gripped by the jaws thereof being indicated in dotted lines.

Figure 2 is a plan view looking upward at the mechanism shown in Figure 1, the radiator column being indicated in solid lines; and

Figure 3 is a longitudinal sectional view of the device through the point of pivotal support of the jaw supporting lever member.

Referring to the drawing in detail, a plani-

form back member 1 is made of sheet metal with an upset lug 2 stamped from the metal thereof to limit the downward pivotal movement of a radiator gripping lever member. A pivotal support member 3 is riveted and comprises an enlarged flanged upper portion 4 which overlies the sides of a slotted opening 5 in a lever 6, a reduced intermediate portion 7 which rides in the slotted opening 5 and a still further reduced lower portion 8 which is adapted to fit closely in a circular opening in the backing plate 1 and extends below the lower face of said plate.

The lower end of the reduced lower portion 8 is riveted outwardly as at 9 to grip the backing plate 1 to hold the pivotal support member 3 firmly in position therein. A central opening 10 is provided in this pivotal support member of a size to receive a bolt or lag screw 11 by means of which the device may be secured in position on a supporting wall. The sides of the lever 6 are bent upwardly as at 12 and 13, the upper side 12 being formed with an extension 14 which forms a jaw to grip a radiator column 16 beyond its central diameter.

Practically all of the radiators manufactured at present are of the narrow column or tube type so that one type of radiator hanger will be suitable for hanging any of the present types of tube radiators. The lower side 13 of the lever 6 is extended upwardly as at 17 and has an edge portion 18 parallel to the back plate 1 to support the rear edge of the radiator column, while a second projecting portion 15 is extended upwardly and formed substantially the same as the projecting portion 14 with the gripping face 19 thereof reversed to grip the opposite side of a radiator column. The jaws 14 and 15 are preferably spaced apart a sufficient distance to grip the radiator column when the lever is inclined slightly upward as in Figure 1, although this spacing of the jaws is not essential provided that the jaws are spaced sufficiently far apart to receive a radiator column between them and not so far as to prevent their gripping the column.

In hanging a radiator with a hanger of this type, a plurality of the hangers are secured

to the wall at required distances, one hanger being required for approximately each three hundred pounds of radiation to be supported. The radiator is then placed in position 5 against the wall with certain of the columns thereof registering with the hanger. The radiator is then moved in toward the wall, the columns thereof registering with said hangers being inserted between the jaws of 10 said hangers. The radiator is then raised as by means of a block and lever in accordance with a well known manner of raising radiators and as the radiator is raised and released the jaws grip the columns of the radiators 15 and hold them in raised position. In case the radiator is raised higher than the required position it may be lowered a small amount at a time by tapping the under side of the outer jaw 15 with a hammer or other 20 instrument, the jaws releasing a slight amount at a time so as to permit very accurate positioning of the radiator.

The back plate 1 is not essential to the operation of the device, although it is desirable, since it provides a smooth surface for the lever 6 to work against and also permits the use of the stop 2 which limits the downward pivotal movement of the lever 6 and thus facilitates the positioning of the radiator in the hangers.

The device comprises a simple and sturdy hanger with no loose parts to become lost in transit and is extremely simple and economical to manufacture. By providing 35 hangers with jaws of a length to extend outwardly beyond the central diameter of the column the hanger can be readily manufactured to hang any wall-supported type of column radiator.

40 I claim:

A radiator support comprising an anchored member adapted to be fixed to a wall, and a lever-acting supporting member having oppositely disposed gripping jaws 45 adapted to grip the radiator tube under the action of gravity, said supporting member being connected to said anchoring member by a pivot that includes a slot extended longitudinally of said lever-acting support 50 and permits sliding adjustments thereof onto said pivot to vary the operative position of said gripping jaws.

In testimony whereof I affix my signature.

FRANK W. FULLER.
